DESIGN FOR A LAMP

Louis Kmiec, Trenton, N. J.

Application August 20, 1948, Serial No. 148,212

Term of patent 3½ years

(Cl. D48—20)

To all whom it may concern:

Be it known that I, Louis Kmiec, a citizen of the United States, residing at Trenton, Mercer County, State of New Jersey, have invented a new, original, and ornamental Design for a Lamp, of which the following is a specification, reference being had to the accompanying drawing, forming part hereof.

I claim:

The ornamental design for a lamp, as shown.
LOUIS KMIEC.
